THROAT PLATE FOR SEWING MACHINES

Frederick F. Zeier, Stratfield, Conn., assignor to
The Singer Manufacturing Company, Elizabeth, N. J., a corporation of New Jersey

Application September 25, 1945, Serial No. 618,484

2 Claims. (Cl. 112—260)

1

This invention relates to sewing machines and more particularly to sewing machine throat-plates.

The invention has for its primary object the provision of an improved throat-plate which will effectively dissipate the force of the successive blows directed thereupon by a work-engaging element, to the end that the noise and vibration resulting from the blows are materially lessened.

With the above and other objects in view, as will hereinafter appear, the invention comprises the devices, combinations and arrangements of parts hereinafter set forth and illustrated in the accompanying drawings of a preferred embodiment of the invention and the advantages attained thereby will be readily understood by those skilled in the art.

When a sewing machine is operated at speeds of 5000 R. P. M., a presser-foot opposed to a lower four-motion feed-dog has a tendency to remain slightly elevated above the throat-plate or, if it does engage the throat-plate, it will exert so little downward pressure that the effectiveness of the work feeding mechanism is substantially reduced. To overcome this objection, it has become the practice to increase the presser-bar spring pressures to the end that the presser-foot will be maintained under pressure in engagement with the work at all times, in spite of the high speed operation of the machine. However, by thus increasing the presser-bar spring pressure in a machine of the present type in which a reciprocating presser-foot and a top feed-foot are employed, it has been found that excessive noise and vibration have been set up. This noise and vibration result from the force of the successive blows directed upon the throat-plate by the reciprocating presser-foot and the top feed-foot. This noise and vibration are particularly objectionable when the machine is operating in the low or medium speed ranges, as it is at this time that the full presser-bar spring pressure would not be required to prevent the presser-foot from lifting off the work.

The present improvement was devised in order to obviate the above noted difficulties.

In the accompanying drawings, Fig. 1 represents a top plan view of a portion of a sewing machine bed-plate with a throat-plate secured thereto.

2

Fig. 2 represents a vertical section of the machine taken substantially along line 2—2 of Fig. 1 and it also discloses portions of a sewing machine feeding and stitching mechanisms.

5 Fig. 3 represents an enlarged vertical section of the bed-plate and throat-plate taken substantially along line 3—3 of Fig. 1.

10 Fig. 4 represents a vertical section of the bed-plate and throat-plate taken substantially along line 2—2 of Fig. 1 and it also discloses portions of a sewing machine feeding and stitching mechanisms.

15 Fig. 5 represents a diagrammatic illustration of the upper feeding and presser-foot elements which are primarily illustrated in Fig. 4.

20 The present invention is herein illustrated as applied to a machine of the type disclosed in my U. S. Patent No. 2,292,258, issued August 4, 1942. That portion of the sewing machine shown comprises a bed 1 upon which is suitably mounted the work-supporting bed-plate 2 fitted with a throat-plate 3. Mounted below the throat-plate 3, is the usual feed-bar 4 having a feed-dog 5 which operates through the throat-plate slots 6 and 7 for the purpose of cooperating with an upper feed-dog 8 in the feeding of the work over the bed-plate 2. Disposed above the throat-plate 3 is a vertically reciprocating presser-foot 9 and the usual needle 10 which, in the machine illustrated, cooperates with the feed-dogs 5 and 8 in the feeding of the work. Cooperating with the needle 10 in the formation of stitches is a loop-taker 11 which is mounted below the throat-plate in the usual manner.

25 35 Referring more particularly to the present invention, the steel throat-plate 3 is mounted, by means of screws 12, upon a substantially C-shaped steel saddle comprising a cross-member 13 and legs 14 and 15. As may be best seen in Fig. 2, the cross-member 13 is beveled in order to afford proper clearance for the feed-bar 4.

30 40 The leg portions 14 and 15 of the saddle underlie the bed-plate edge portions as at 16 in order to afford means whereby the saddle may be secured to the under portions of the bed-plate 2. Bolts 17 are provided for securing the saddle to the bed-plate. The upper portion of these bolts are formed with shoulders 18 abutting the lower surface of the bed-plate 2, which latter is provided with apertures for the purpose of receiv-

ing the heads of the bolts. These bolt heads are riveted over as at 19 against a spot-faced portion of the bed-plate, thereby to permanently secure the bolts in depending relation therewith.

As may be best seen from Fig. 3, the saddle-legs 14 and 15 are suitably bored to receive the bolts or posts 17, of which the lower ends are threaded as at 20 in order to receive the nuts 21.

The upper faces of the saddle-legs 14 and 15 are recessed to receive fiber or rubber washers 22 which are interposed between said legs and the bed-plate 2 to completely insulate the saddle from the bed-plate. Collars 23 of the same material embrace the bolts within the bores of the legs, thereby effectively to prevent the bolts 17 from engaging the saddle legs.

In order to urge the throat-plate 3 resiliently towards the presser-foot 9, there are provided coil-springs 24 which are interposed between the nuts 21 and steel washers 25. Placed between each of these steel washers 25 and the shouldered portions of leg-apertures 26 are a pair of fiber or rubber washers 27 which completely insulate the springs 24 and steel washers 25 from the legs 14 and 15. The tension of the springs 24 may be varied by adjusting the positions of the nuts 21 upon the bolts 17.

Referring to Fig. 4, the machine illustrated is provided with a needle-feed mechanism as shown in my U. S. Patent No. 2,329,681, September 14, 1943. In the present instance, the needle-bar frame 28 has a bearing lug 29 in which the top feed-bar 30 is slidably mounted so that the frame 28 will vibrate the feed-bar 30 in the line of feed along with the needle-bar 31.

The usual type of top-feeding foot 8 is carried by the lower end of the top feed-bar 30 whose upper end is provided with a cross-pin 32 which is slidably received within the forked free end 33 of a substantially horizontally disposed feed-lift crank 34. The confined end of this crank is pivotally carried as at 35 by the rear portion of the machine head 36.

The machine head 36 is provided with a vertically disposed stationary bearing member 37 in which a presser-bar 38 is slidably mounted. The usual type of presser-foot 9 is carried by the lower end of the presser-bar 38. Formed in the upper portion of the presser-bar 38 is a slot 39 adapted to receive one arm 40 of a bell-crank lever which is pivotally carried by and at the center of percussion 41 of the crank 34. The other arm 42 of the bell-crank lever is connected by means of a link 43 to an actuating crank 44 carried by a rock-shaft 45 which is journaled in the machine head 36 in parallel relation with the main shaft 46. An eccentric 47 carried by the main shaft 45 imparts rocking movements to this rock-shaft 45 by means of a connecting pitman rod 48.

Bearing downwardly upon the feed-lift crank 34, at a point between the bell-crank pivot point 41 and the free end thereof, is one end of a spring-depressed lever 49 which extends backwardly along the machine bracket-arm. A steel ball 50 is placed between the spring lever 49 and feed-lift crank 34 in order to prevent the spring lever from exerting any side thrust upon the latter element.

The oscillating motions of the above noted rock-shaft 45 cause the bell-crank lever to swing in a vertical plane about its pivot 41 in the feed-lift crank 34, so that the arm 40 of the bell-crank lever tends successively to lift and depress the presser-bar 38. When the presser-bar is de-

pressed, however, its presser-foot 9 engages the work upon the throat-plate 3 and further movement of the bell-crank lever can only result in raising the pivot point 41 thereof, which latter action will, of course, raise the free end 33 of the feed-lift crank 34 with the consequence that the top feed-bar 30 is lifted clear of the work. Continuous oscillations of the rock-shaft will, therefore, cause the presser-bar 38 and the top feed-bar 30 alternately to rise and fall, and the spring-depressed lever 49 being in continuous engagement with the feed-lift crank 34, will have its force transmitted either to the presser-bar or to the top feed-bar, depending upon which one of the two elements is in engagement with the throat-plate or work. The motions of the rock-shaft 45 are synchronized with those of the needle-bar 31 so that the usual compound feeding motions will be effected.

From the above, it may be readily understood that the rapidly reciprocating feet 8 and 9, impart successive blows upon the throat-plate 3 which would result in the production of undesirable noises and vibration if the present throat-plate was not provided with means whereby the force of the blows could be absorbed.

Thus, as the present throat-plate is supported by the coil-spring means, it is adapted to absorb the hammer blows of the feet 8 and 9. Furthermore, the provision of the non-metallic washers and collars completely insulate the throat-plate from the machine bed to the end that the throat-plate cannot transmit any of its vibrations to the machine proper.

As a further means to help dampen the undesirable vibrations, the throat-plate has provided thereon the relatively massive saddle member which comprises essentially a plurality of vibration-absorbing protuberances 14 and 15. The added mass of this saddle unit is effective to alter, to an advantage, the natural vibration frequency of the throat-plate.

From the foregoing description, considered in connection with the accompanying drawings, the construction, manner of operation and several advantages of this improved throat-plate unit will be clearly and fully understood. It is apparent that such a unit has a wide variety of uses, and it will be understood that the form, construction and arrangement of the elements employed may be varied. Therefore, the privilege is reserved of resorting to all such legitimate changes therein as may be fairly embodied within the spirit and scope of the appended claims.

Having thus set forth the nature of the invention, what I claim herein is:

1. A sewing machine having a frame provided with a bed-plate and an overhanging head, a pair of reciprocatory work-engaging elements adapted alternately to engage the work on one side thereof, a movable work-engaging element disposed on the other side of the work and arranged to oppose one of said pair of work-engaging elements, a throat-plate opposed to the other of said pair of work-engaging elements, and vibration absorbing devices interposed between said throat-plate and frame to insulate said throat-plate from metal-to-metal engagement with said frame.

2. A sewing machine having a frame provided with a bed-plate and an overhanging head, a pair of reciprocatory work-engaging elements adapted alternately to engage the work on one side thereof, of, a movable work-engaging element disposed

on the other side of the work and arranged to oppose one of said pair of work-engaging elements, a throat-plate opposed to the other of said pair of work-engaging elements, a saddle member to which said throat-plate is secured, said saddle member having a mass greater than that of said throat-plate, and vibration absorbing means interposed between said saddle and said bed-plate.

FREDERICK F. ZEIER.
